CLAIM

The ornamental design for a pet feeding system, as shown and described.

DESCRIPTION

FIG. 1 is a perspective view of the pet feeding system according to a first embodiment of the present invention.

FIG. 2 is a front view of the pet feeding system illustrated in FIG. 1.

FIG. 3 is a rear view of the pet feeding system illustrated in FIG. 1.

FIG. 4 is a side view of the pet feeding system illustrated in FIG. 1, as viewed from the left side of FIG. 2, the other side being a mirror image thereof; and,

FIG. 5 is a top plan view of the pet feeding system illustrated in FIG. 1, in which the circular forms drawn inside of the lower interior bowl compartment depict openings.

The only unclaimed portion of the pet feeding system is the elongated rectangular form depicted in unclaimed broken line on the front of the lower base of the invention visible in FIGS. 1 and 2. All other incontiguous lines are employed to depict contours of the invention.
